UNITED STATES PATENT OFFICE

121,482

DESIGN FOR A COMBINED BROOCH AND FLOWER HOLDER

Victor Silson, New York, N. Y.

Application April 27, 1940, Serial No. 91,991

Term of patent 3½ years

To all whom it may concern:

Be it known that I, Victor Silson, a citizen of the United States of America, residing in the city of New York, county of New York, and State of New York, have invented a new, original, and ornamental Design for a Combined Brooch and Flower Holder, of which the following is a specification, reference being had to the accompanying drawing, forming part thereof.

Fig. 1 is a plan view of a combined brooch and flower holder showing my new design.

Fig. 2 is a rear view thereof.

Fig. 3 is an edge view.

Fig. 4 is a cross section taken on line 4—4 of Fig. 2.

I claim:

The ornamental design for a combined brooch and flower holder, substantially as shown.

VICTOR SILSON.
